UNITED STATES PATENT OFFICE.

LILLIAN WORMSER, OF TRENTON, NEW JERSEY.

DESIGN FOR A BOX FOR ASH-SIFTERS.

SPECIFICATION forming part of Design No. 29,103, dated July 26, 1898.

Application filed June 14, 1898. Serial No. 683,441. Term of patent 3½ years.

To all whom it may concern:

Be it known that I, LILLIAN WORMSER, a citizen of the United States, residing at Trenton, in the county of Mercer, State of New Jersey, have invented and produced a new and original Design for the Box of an Ash-Sifter, of which the following is a specification, reference being had to the accompanying drawings, forming part thereof.

The leading feature of my design for the box of an ash-sifter is a box having a flange on the sides of the bottom thereof, a diverging neck pendent from said bottom, and a vertical collar pendent from said neck.

Figure 1 represents a perspective view of the box of an ash-sifter embodying my design. Fig. 2 represents a longitudinal vertical section thereof.

In the drawings, Δ designates the box of an ash-sifter, at the sides of the bottom of which is the laterally-projecting flange B. Depending from said bottom is the diverging neck C, and depending from the latter is the vertical collar D.

E designates the lid of the box.

Having thus described my invention, what I claim as new, and desire to secure by Letters Patent, is—

The design for the box of an ash-sifter, substantially as shown and described.

LILLIAN WORMSER.
